US00D853053S

(12) **United States Design Patent** (10) **Patent No.:** **US D853,053 S**
O'Donnell et al. (45) **Date of Patent:** **** Jul. 2, 2019**

(54) **ANIMAL FEEDING APPARATUS**

(71) Applicant: **Curio Holding Company**, Philadelphia, PA (US)

(72) Inventors: **Dennis P. O'Donnell**, Philadelphia, PA (US); **Eric Griffin**, Philadelphia, PA (US); **Keith Hatton**, Philadelphia, PA (US); **John Combs**, Philadelphia, PA (US); **Kurt Swanson**, Philadelphia, PA (US); **Devin Sidell**, Philadelphia, PA (US)

(73) Assignee: **Curio Holding Company**

(**) Term: **15 Years**

(21) Appl. No.: **29/686,080**

(22) Filed: **Apr. 2, 2019**

Related U.S. Application Data

(63) Continuation of application No. 15/267,348, filed on Sep. 16, 2016.

(51) **LOC (11) Cl.** **30-03**

(52) **U.S. Cl.**

USPC **D30/129**

(57)

CLAIM

The ornamental design for an animal feeding apparatus, as shown and described.

DESCRIPTION

FIG. 1 is a front perspective view of an animal feeding apparatus according to the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
